COOLING SYSTEM FOR COMPRESSORS

Leslie B. M. Buchanan, Springfield, Mass., assignor to Westinghouse Electric & Manufacturing Company, East Pittsburgh, Pa., a corporation of Pennsylvania

Application June 5, 1936, Serial No. 83,617

6 Claims. (Cl. 230—208)

My invention relates to cooling systems for motor driven compressor mechanisms of the hermetically-sealed type and has for an object to provide an improved system.

5 A further object of my invention is to provide an improved cooling system for apparatus of this kind wherein a heat exchanging fluid such as, for example, lubricant is circulated over the apparatus for cooling the same.

10 A further object of the invention is to effect a reduction in the operating temperature of conventional mechanisms of this kind without increasing the amount of lubricant that is circulated.

15 A still further object of my invention is to provide an improved system for cooling the resiliently mounted, hermetically sealed motor compressor unit of a refrigerating machine.

20 These and other objects are effected by my invention as will be apparent from the following description and claims taken in connection with the accompanying drawing, forming a part of this application, in which:

25 Fig. 1 is a vertical sectional view of a hermetically sealed motor driven compressor employing my novel system of cooling;

30 Fig. 2 is a diagrammatic view of a conventional oil cooling system for a motor driven compressor mechanism with oil temperatures indicated thereon;

Fig. 3 is a view similar to Fig. 2 but including my improved oil cooling system and having oil temperatures indicated thereon; and,

35 Fig. 4 is a view of a novel pump structure which may form a part of my improved cooling system.

Heretofore, it has been the practice to cool the hermetically sealed motor compressor units of refrigerating machines, and particularly resiliently mounted units of this kind, by passing oil in heat exchanging relation therewith. The oil heated by the unit then drains to a sump and is withdrawn therefrom by a pump. A portion of the oil discharged by the pump is passed in heat exchanging relation with the casing for cooling thereby, and a second portion is delivered to the compressor unit for abstracting heat therefrom.

In accordance with my invention, the heated oil discharged from the motor and compressor is collected and passed directly to the casing for cooling prior to its discharge to the sump. Means are provided for withdrawing cooled oil from the sump and conveying it to the motor compressor unit where it performs its cooling action. In circulating the oil in this manner,

I am enabled to operate the unit at a lower temperature than is possible with the prior method of circulation and without increasing the total quantity of oil that is circulated per unit of time. In the drawing, Figs. 2 and 3 disclose, respectively, a method of circulation employed heretofore and my improved system of circulation. Temperatures of the oil at various stages of its circulation are indicated on these views. Further reference to these figures will be made 10 hereinafter.

Referring now to Fig. 1 of the drawing, I show my improved cooling system applied to a hermetically sealed refrigerating machine which includes a compressor 10 driven by an electric motor 11 having a shaft 9, the motor and compressor being enclosed by a casing structure 12. As shown, the motor 11 and compressor 10 define a unit structure with the compressor superimposed upon and carried by the motor 11, but it will be understood that the invention is equally applicable to units wherein the compressor is disposed beneath the motor. Furthermore, it is equally applicable to units employing motors and compressors of the horizontal type. The 25 hermetic casing 12 may include a base member 13 and a shell 14 secured thereto. Suitable means, such as, for example, a cooling coil 14a may be employed for abstracting heat from the shell 14 in a well understood manner. It will be obvious 30 that the casing may be cooled in any other suitable manner, such as, by radiation to the ambient atmosphere.

My invention may be applied to units that are directly connected to the enclosing shell, 35 but it is particularly adaptable to units which are resiliently supported therein. Accordingly, I show resilient members or springs 15 supported by the casing structure 12 for carrying the motor 11 and compressor 10. Any suitable means for 40 attaching the springs 15 to the casing 12 may be employed such as, for example, lugs 16 secured to the shell 14. Lugs 17 may be formed on the motor 11 for attachment to the opposite ends of the springs 15. With this arrangement, vibrations originating in motor 11 and compressor 10 45 are damped by the springs 15 and are not transmitted to the casing 12, whereby quiet operation is obtained.

Compressed refrigerant is delivered to a condenser 18 by means of a conduit 19 which passes through the casing 12 as shown. The evaporator of the refrigerating system is shown at 21 and connects with the condenser 18 through a suitable pressure reducing device 22. A conduit 23 55

conducts vaporized refrigerant from the evaporator 21 to the interior of the casing 12 from which it is withdrawn by the compressor 10 and compressed. By admitting cool vapor from the evaporator to the interior of the casing, advantage is taken of the cooling action thereof.

Heat generated by the motor 11 and compressor 10 is abstracted by passing a heat exchange medium, such as the lubricating oil, in heat exchanging relation with the motor and compressor. The oil is subsequently passed over the interior surface of the shell 14 for cooling and the heat abstracted therefrom by the shell is conducted to its cooling coil 14a or radiated to the ambient atmosphere. The bottom portion of the casing 12 defines a sump 24 for the cooled oil that drains by gravity from the interior surface of the shell 14.

In accordance with my invention, I provide a pair of pumps 25 and 26 beneath the compressor and motor and, preferably, driven by the shaft 9. The pumps 25 and 26 may have a common casing 27 divided into a pair of pump chambers 28 and 29. A receptacle 31 is disposed beneath the motor 11 for receiving heated oil which drains by gravity from the compressor 10 and motor 11. The receptacle 31 and pump casing 27 are preferably carried by the motor 11 and, as shown, the receptacle 31 is secured to a frame member 32 of the motor 11 and the pump casing 27 is fixed to the receptacle 31.

The lower pump 25 operates to circulate cooled oil from the sump 24 through a conduit 33 which extends upwardly and terminates above the motor 11 and adjacent to the compressor 10. Cool oil discharged by the conduit 33 is diffused over the compressor 10 and motor 11 for the abstraction of heat therefrom. The pump 25 draws oil from the sump 24 through an opening 34 that is formed in the casing 27 and preferably submerged in the pool of oil.

The upper pump 26 has an inlet passage 35 communicating with the receptacle 31 through which heated oil is drawn prior to its discharge through a conduit 36 which extends upwardly and terminates adjacent the top of the shell 14. Heated oil discharged by the conduit 36 flows radially over the inside surface of the top of the shell and thence downwardly toward the sump 24 in a cylindrical film within the side walls of the casing. Cooling of the oil is effected during this passage by the relatively cool walls of the casing 14. A baffle 37 may be disposed between the discharge ends of the conduits 33 and 36 for preventing mixture of oil which may be splashed during discharge and for preventing heated oil from dropping to the motor or compressor.

In Fig. 2, I have diagrammatically shown the cooling system for hermetically sealed refrigerating systems employed heretofore with temperatures indicated thereon. The numeral 41 indicates a motor compressor mechanism of the type shown in Fig. 1 and driving a single pump 42. The pump 42 draws oil from the sump 43 and discharges approximately half of it over the casing 12 and a second half over the unit 41. The heated oil drops to the sump 43 where it mixes with the cooled oil draining from the casing walls. In the following comparison, I am assuming that one gallon of oil is delivered to the casing and one gallon to the mechanism 41, per unit of time. Fig. 3 diagrammatically illustrates my improved system shown in Fig. 1 with oil temperatures shown thereon. I am assuming that each pump 25 and 26 is pumping one gallon of oil per unit of

time over the motor mechanism and the casing, respectively. There is, therefore, one gallon of oil circulated over the motor mechanisms and one gallon over the casing in each case.

I am assuming an average shell temperature of 150° in both cases, which indicates that the watts or B. t. u. input to the shell is the same in both cases. I am, furthermore, assuming a 20° temperature rise in the oil passing over the motor mechanism due to the heat abstracted therefrom. It will be apparent from Figs. 2 and 3 that I obtain a 20° cooler motor mechanism than is obtained by the oil cooling system used heretofore. This is due to the fact that a lower temperature oil is available in the sump for circulation to the motor mechanism. In the prior system, the oil cooled by the casing is mixed with the relatively hot oil drained from the motor mechanism so that the resultant temperature is higher than the temperature of the cooled oil. In my improved system, this mixing is obviated by circulating all of the heated oil to the casing for cooling and passing all of the cooled oil withdrawn from the sump to the motor mechanism.

It will be apparent that the differential between the motor and the shell in Fig. 2 is greater than in Fig. 3, although the shell temperatures are the same, the motor temperature in Fig. 2 being at a higher value for the same shell temperature than the motor of Fig. 3. When the load is increased by the same amount on the motors shown in Figs. 2 and 3, the temperatures of the two shells will increase by substantially the same amount and the amount of heat removed therefrom will also increase. However, assuming that the safe operating temperatures of the two motors are the same, then for a given increase in load and with the same shell temperatures, the motor of Fig. 2 will rise above the safe operating temperature before the motor of Fig. 3 because of the greater temperature differential between the shell and the motor in the arrangement shown in Fig. 2. Obviously, the shell temperature for a given load in either case depends on the temperature of the cooling fluid surrounding the shell. From the two disclosed methods of heat removal, it will be apparent, therefore, that a greater load can be carried by the motor of Fig. 3 than by the motor of Fig. 2 without exceeding a safe operating temperature.

Fig. 4 shows an arrangement of circulating the warm and cool oil in a single pump structure of the centrifugal type. The pump includes a casing 51 having opposed volutes 52 and 53 and a single runner 54 which may be driven by the shaft 9. Opposed inlet ports for the hot and cool oil are shown at 55 and 56, respectively. Conduits 57 and 58 may connect, respectively, with the receptacle 31 and sump 24 of the apparatus shown in Fig. 1. The volutes 52 and 53 terminate in outlet passages 59 and 61 which may communicate respectively with the conduits 36 and 33 of Fig. 1.

With this structure, the single runner 54 translates heated oil entering through the port 55 through the conduit 36 and the cool oil entering through the port 36 to the conduit 33 without mixture of the separate streams of oil.

From the foregoing, it will be apparent that I have provided an improved oil cooling system for a hermetically sealed motor compressor mechanism wherein the operating temperature is maintained at a relatively low value and wherein relatively large overloads may be carried without seriously overheating the motor. I have, during this description, referred to the heat transfer

medium as oil, but it will be understood that other media may be employed. Furthermore, I have shown a refrigerating machine wherein the casing defines a chamber communicating with the suction conduit leading from the evaporator, but it is to be understood that this is shown by way of example and that this chamber may connect to other portions of the refrigerant circuit or may be isolated from the circuit completely.

10 While I have shown my invention in two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In a cooling system the combination of a compressor, a motor for driving the same, a casing for housing the motor and compressor and having a sump formed therein for collecting lubricant drained by gravity from the casing, a receptacle disposed beneath the motor for collecting lubricant drained by gravity from the motor, a pump for conveying the heated lubricant in the receptacle in heat exchanging relation with the casing, and a second pump for conveying the cooled lubricant in the sump to the motor and compressor for cooling the same.

2. In a cooling system, the combination of a substantially vertical motor, a compressor driven thereby, a hermetic casing for housing the motor and compressor and including a lubricant sump disposed at the bottom thereof, a receptacle arranged beneath the motor and compressor for collecting heated lubricant discharged therefrom, means for passing the heated lubricant in the receptacle in heat exchanging relation with the casing whereby the lubricant is cooled as it drains by gravity to the sump, and means for conveying the cooled lubricant from the sump to the motor and compressor for cooling the same.

3. The combination as claimed in claim 2 having resilient means for supporting the motor and compressor and carried by the casing.

4. In a cooling system for a refrigerating machine, the combination of a substantially vertical motor, a compressor driven thereby, a hermetic casing structure for housing the motor

and compressor, resilient means carried by the casing structure and supporting the motor and compressor, means defining a sump within the casing structure for cooled lubricant, a receptacle carried by the motor for collecting heated lubricant discharged by the motor and compressor, means driven by the motor for conveying heated lubricant from the receptacle in heat exchanging relation with the casing structure for cooling thereby, and means driven by the motor for conveying cooled lubricant from the sump to the motor and compressor for cooling the same.

5. In a cooling system for a refrigerating machine, the combination of a substantially vertical motor, a refrigerant compressor superimposed on the motor and driven thereby, a hermetic casing structure enclosing said motor and compressor and defining a cooling surface for lubricant, said casing having a sump formed therein for collecting lubricant cooled by the casing, resilient means carried by the casing structure and supporting the motor, a receptacle carried by the motor for collecting lubricant heated thereby, means driven by the motor for conveying heated lubricant from the receptacle in heat exchanging relation with the casing and a second means for conveying cooled lubricant from the sump in heat exchanging relation with the motor.

6. In a cooling system for a refrigerating machine, the combination of a compressor, a motor for driving the same, a casing for housing the motor and compressor and defining a cooling surface for a heat exchanging medium, said casing having a sump formed therein for the cooled medium, a receptacle disposed beneath the motor and compressor for receiving heated medium discharged thereby, a single pump structure having first and second inlet passages therein communicating, respectively, with said sump and receptacle, said pump having first and second passages formed therein for the discharge of media entering the pump through said first and second inlet passages respectively, means for conveying medium from the first outlet passage to said motor and said compressor for cooling the same, and means for conveying medium from the second outlet passage in heat exchanging relation with the casing for cooling thereby prior to its admission to the sump.

LESLIE B. M. BUCHANAN. 50
